1 Inventor:
LAWRENCE M. PERSONS.

By Jones, Addington, Ames, Peabody, Atlys.

UNITED STATES PATENT OFFICE

LAWRENCE M. PERSONS, OF CHICAGO, ILLINOIS, ASSIGNOR TO COOK ELECTRIC COMPANY, OF CHICAGO, ILLINOIS, A CORPORATION OF ILLINOIS

PUMP

Original application filed July 13, 1925, Serial No. 43,064. Divided and this application filed February 1, 1926. Serial No. 85,370.

My invention relates to systems for pumping liquid into a tank or receptacle and more particularly to a motor driven pump, having as one of its characteristics the ability to 5 operate automatically upon the withdrawal of liquid from the tank or receptacle.

This application is a division of my co-pending application, Serial No. 43,064, filed July 13, 1925.

10 In the automatic operation of a motor driven pump, means are usually employed to control the circuit to the motor according to some operating condition of the pump. This means may comprise a float control 15 switch mechanism arranged to close the circuit when the liquid in the receptacle falls below a predetermined low level. It will be seen that the operation of the pump is, therefore, automatic and that the pump will start 20 pumping when the liquid therein reaches a predetermined low level. It has been found, however, that the lowering of the liquid level is not always the result of an operating condition, inasmuch as leaks frequently occur 25 in the pipe line between the receptacle and the point where the liquid is consumed. On the other hand, in oil burning systems, the oil burner often causes an abnormal drain on the receptacle when the needle valve of the float 30 mechanism of the burner fails to work.

If the float controlled switch mechanism closes the circuit when the liquid level lowers in the receptacle, the pump will continue to feed the liquid to the receptacle until the level 35 is again restored, but should a leak occur as stated, or should the oil burner place an overload on the pump, this level will not be restored automatically and it is possible for the pump to continue pumping and empty the 40 bulk supply tank of the oil burning system before this condition will be observed. In the event of a leak in the pipe line, the possible conflagration of the fuel emptied on the basement floor where the oil burner is located is 45 clearly apparent.

One of the objects of my invention is to provide an improved safety control for a motor driven pump adapted to feed liquid fuel, fed to an oil burner or the like, which 50 will eliminate the above referred to difficul-

ties of the prior art devices by the provision of a safety means of simplicity, which is accurate and efficient in operation and devoid of intricate mechanism which is apt to require constant attention and frequent repair. 55

In carrying out my invention I embodied the aforesaid safety means preferably within a small receptacle associated with the pump, so that when the fuel is entirely withdrawn from the receptacle, or is withdrawn below a predetermined low level, as the case may be, as the result of an overload on the pump, the latter is immediately rendered inoperative. 60

In this respect my invention is an improvement over a co-pending application, Serial No. 30,578, filed May 15, 1925, in which there has been disclosed and broadly claimed, a pump of the type herein shown, and in which is disclosed a novel form of structure for disabling the operation should the liquid be withdrawn therefrom at a rate greater than what is normally controlled by the burner. The present invention provides a very simple and efficient means for accomplishing this result, being in the form of a single float capable of opening the circuit of the motor when in its upper or lower positions. Hence, the float serves to disable the operation of the pump when the fuel in the said receptacle has reached a predetermined high level, to start the pump when the fuel drops below this high level, and to stop the pump when the fuel has been withdrawn below a predetermined low level. The latter may be the result of the liquid being drawn from the receptacle or pump at a rate greater than the normal consumption by the oil burner, or whatever liquid consuming device that is employed. 70 75 80 85

Further objects and advantages of my invention will be apparent from the following description when taken in connection with the accompanying drawings forming a part hereof. 90

In the drawings:

Figure 1 is a view, partly in vertical section and partly in elevation, of a pump embodying my invention;

Fig. 2 is a diagrammatic view of an oil burning system for the purpose of illustrat-

ing one of the many different systems that may employ this pump;

Fig. 3 is an enlarged detail elevational view of the switch mounting;

Fig. 4 is a sectional view taken on line 4—4 of Fig. 3; and

Fig. 5 is a horizontal sectional view of one end of the mercury switch illustrating the electrodes bridged by a body of mercury.

10 In the operation shown in Fig. 1 the oil or liquid from the storage tank 5 or other source of supply is drawn through a suction pipe 6 by means of a pump 7 and is fed through an outlet pipe 8 into a tank or receptacle 10.

15 Pump 7 is driven by an electric motor 9.

The automatic safety control disclosed herein comprises a float 12 mounted in any suitable manner within the tank, as for instance on a rod 13, so that it will be guided 20 on the rod as it moves up and down. An electric switch 14 is actuated by float 12 to cause the automatic starting and stopping operations above set forth.

Switch 14 is provided in the motor circuit 25 and is preferably of the mercury type, having a pair of electrodes adapted to be bridged by a body of mercury when the switch is in closed position. A depending bracket 15 is adapted to be fastened to the underside of the top 30 of tank 10 by a screw 16. Sides 17 of depending bracket 15 are apertured at 18 to receive the pivotal lugs 19, extending transversely from the sides of a carriage 20 on which mercury switch 14 is disposed. As illustrated 35 in detail in Fig. 3, the carriage 20 comprises a plate on which side clips 21 are mounted to receive mercury switch 14.

Said side clips 21 have lugs 22 struck up from their sides to clip conductor carrying 40 members 24 at the sides so that the lead in wires of the mercury switch may be brought forwardly to the front and connected to the electrodes of the mercury 2, as illustrated at 25 in Fig. 3.

45 The opposite ends of these conductors are protected by flexible armoured coverings 26 which are fastened into an insulation collar 27. Bracket 15 may be provided with a depending arm 28 for carrying collar 27 and 50 detachable plug connection 29 for the motor conductors 30 and 31 extending upwardly into the motor housing through a sleeve of insulation 32.

One end of plate 20 extends integrally 55 downwardly at a slight angle to carry a buffer 33, which is adapted to be engaged by float 12 when the float is raised to its maximum high level for the purpose of opening the circuit to the motor 9. The opposite end of plate 20 60 is furnished with an arm 35. The upper end of rod 13 is bent substantially at a right angle as indicated at 36 to pivotally connect to extension 35 at 37. A collar 38 is fastened to stem 13 adjacent to the lower end of the stem.

In the normal operation of the device the

liquid will be withdrawn through the delivery pipe or outlet 45, thereby causing the liquid in receptacle 10 to be lowered below line A—B, illustrated in Fig. 1. Float 12 will move with the liquid and release the switch 70 14 from its open position by disengaging the buffer 33. The switch is then permitted to tilt in the direction of the buffer, by gravity, about its pivots 19. The circuit to the motor is thereby closed and the pump 7 is operated 75 to draw liquid out of the storage tank 5 and to feed it through pipe 8 into receptacle 10.

If the additional liquid thus supplied permits the level A—B to be again obtained, the switch 14 is tilted upwardly to open position 80 by float 12, engaging the buffer 33 and moving it upwardly. If, however, after continuous pumping of additional liquid through pipe 8 into tank 10 the level A—B is not obtained, but, on the contrary, the liquid feeds 85 through the delivery pipe faster than it is fed into tank 10, the liquid level will continue to lower float 12 until the float engages lug 38. The weight of the float 12 against lug 38 is sufficient to force stem 13 downwardly, thereby exerting a downward pull on carriage extension 35 to cause pivoting of switch 14 in this direction; that is, in its open position. The circuit to the motor is thereby broken and the pump 7 is temporarily disabled.

A further feature of my invention resides in the provision of an improved resetting mechanism for operating the pump after it has been disabled by float 12 falling to the bottom of the receptacle 10 to open switch 14. With the liquid entirely withdrawn from receptacle 10, this resetting mechanism functions to lift float 12 upwardly a short distance so as to relieve the stem 13 from the weight of the float, as at 38, and thereby permit the switch itself to pivot by gravity to closed position. The circuit to the motor will then be closed. This mechanism may be employed to hold float 12 in the position 100 removing its weight from stem 13 until enough liquid has been pumped into receptacle 10 to continue holding the float away from lug 38.

Said mechanism may comprise a vertical 115 rod 40 extending into tank 10 with its lower end bent at right angles as indicated at 41 to a point below float 12. The other end of rod 40 projects through the top of receptacles 10 and may be provided with a knob 42. A stop 120 43 confines a coil spring 44 between it and the underside of the top of tank 10, so that rod 40 will itself snap into normal position when released at the knob 42. It is apparent that by manually engaging knob 42 and lifting rod 41 upwardly, the float 12 when in its dotted line position as shown in Fig. 1, and lift it upwardly a short distance.

From the foregoing description, it will be readily apparent that an abnormal demand 120

- by the burner or by a leak in the fuel line will immediately cause the float to open the switch and break the circuit to the motor, and to thereby prevent a serious conflagration of fuel that may flood the basement floor where the burner is located. Such an arrangement is particularly unique in cases where the owner of a building may wish to leave the premises for several days and may then set the room thermostat (not shown) to maintain a certain temperature whereby to prevent the pipes of the house from freezing. The Board of Underwriters has found that it is during such periods of absence from the premises that leaks occur in the pipe between the burner and the receptacle 10 and flood the basement and cause serious fires because these leaks at such times usually go unnoticed too long.
10. I wish to emphasize the fact that the feature of providing a triple acting float controlling mechanism capable of shutting down the supply of liquid to any type of receptacle may take many forms other than that illustrated and described herein and that the invention is not limited to oil burning systems.
15. Various other embodiments and modifications of my invention will be apparent to those skilled in the art, and, consequently, I do not intend to be limited to the details herein described and illustrated.
20. I claim:
1. The combination with a motor driven pump, having a switch for controlling the circuit to the motor, of a float for actuating said switch, arranged so that the switch will be open when the float is in raised position, and will be closed when the float is in intermediate position, and will be opened when the float is in lowered position.
  2. In a pumping apparatus, the combination of a source of supply, a receptacle, a motor driven pump for pumping liquid from the source of supply into said receptacle, a switch for controlling said motor, and a float in the receptacle, which is adapted to open the switch when the liquid reaches an upper level, to close the switch when the liquid reaches an intermediate level, and to again open the switch when the liquid reaches a lower level.
  3. The combination with a supply tank, of a motor driven pump for pumping liquid from a storage tank to the supply tank, a float in said supply tank, a switch for controlling the motor, and operative connections between the float and the switch whereby the switch will be swung to open position when the float rises and will be swung to closed position when the float moves downwardly to a predetermined position and the switch will be again swung to open position when the float moves downwardly beyond said predetermined position.
  4. The combination with a receptacle having a float therein, of a switch adapted to be actuated by the float, said float having operative connections with the switch whereby the switch will be automatically thrown to closed position when the float is at a predetermined point and the switch will be thrown to open position if the float moves above or below said predetermined point, substantially as described.
  5. The combination with a quick make and break switch, of an operating member and connections between the switch and operating member whereby the switch will be opened when the operating member is in one position, will be closed when the operating member moves a predetermined distance and will again be opened when the operating member is moved a further predetermined distance in the same direction.
  6. The combination with an electric switch, of an operating member and connections between the operating member and the switch, whereby the switch will be opened when the operating member is in raised position, will be closed when the operating member is in intermediate position, and will again be opened when the operating member is in lowered position.
  7. The combination with a receptacle, of an electrically driven pump for supplying liquid to said receptacle, a switch in the electric circuit of said pump, and a triple acting float in said receptacle for opening and closing said circuit when in different predetermined positions.
  8. The combination with a receptacle, of electrically controlled means for supplying liquid to said receptacle, a switch in the electric circuit of said means, a rod suspended from one end of said switch, and a float movably guided along said rod, said float serving to open said switch by the weight of said float on said rod when said float is in a predetermined low position, and to open said switch by the movement of said float upwardly along said rod when said float is in a predetermined upper position.
  9. The combination with a receptacle and electrically controlled means for supplying liquid to said receptacle, of a switch in the circuit of said means, a float movably guided in said receptacle adapted when in a predetermined upper position to open said switch, and means for limiting the downward movement of said float whereby the weight of said float against said means serves to open said switch.
  10. The combination with a pump, of electrical means for operating said pump, a receptacle for receiving the liquid supplied by said pump, a tiltable mercury switch in circuit with said means, and a float for tilting said mercury switch to open circuit position when the liquid flows from said receptacle in excess of a predetermined rate, said float being arranged also to tilt said mercury

switch to open circuit position when the liquid reaches a predetermined high level in said receptacle.

11. The combination with a receptacle, of a motor driven pump for supplying liquid to said receptacle, a switch in circuit with said motor driven pump, a float connected to said switch adapted to open said switch when the liquid drops to a predetermined level in said receptacle, and means for temporarily disabling the action of said float whereby to close said switch when said float is at said predetermined level.

12. In a device of the class described: a container adapted to hold a liquid, a float therein, an electric switch, connecting mechanism between the float and the switch for opening the switch by the movement of the float in one direction and for closing the switch by a movement of the float in the opposite direction, and for again opening the switch by the continuing movement of the float in the last specified direction.

13. In a device of the class described: a container adapted to hold a liquid, a float therein, a movable member, connecting mechanism between the float and the movable member, for moving said member to one position by the movement of the float in one direction, and for moving said member to another position by the movement of the float in the opposite direction, and for moving said member to its first-mentioned position by continued movement of the float in the last specified direction.

14. In a device of the class described: an electric switch within an electric circuit, mechanism for operating said switch and a float connected to said mechanism for actuating said mechanism, said mechanism having two operative positions for opening the switch circuit and a third operative position for closing said switch circuit.

15. In a device of the class described: a tiltable electric switch within an electric circuit, said switch having two operative positions for breaking the circuit through said tiltable switch, a third operative position for completing the circuit through said tiltable switch, and a float adapted to actuate the switch for making and breaking a circuit in said three operative positions.

In witness whereof, I have hereunto subscribed my name.

LAWRENCE M. PERSONS.
